UNITED STATES PATENT OFFICE.

STEPHEN SZÜCS, OF HOMESTEAD, PENNSYLVANIA, ASSIGNOR OF ONE-FIFTH TO EMRY MIKO, ONE-FIFTH TO GYULA ZOMBORY, AND ONE-FIFTH TO STEPHAN SZINNYEI, ALL OF HOMESTEAD, PENNSYLVANIA.

PARACHUTE.

1,278,253

Specification of Letters Patent. Patented Sept. 10, 1918.

Application filed June 8, 1918. Serial No. 238,847.

To all whom it may concern:

Be it known that I, STEPHEN SZÜCS, a subject of the King of Hungary, residing at Homestead, county of Allegheny and State 5 of Pennsylvania, have invented certain new and useful Improvements in Parachutes, of which the following is a specification.

This invention relates to improvements in devices used in aerial navigation, and particularly to types known as parachutes.

The principal object of the invention is to provide a device engageable with the waist of a person, whereby an impedance is caused in the downward passage through the 15 air.

Another object is to provide means which may be readily attached to a person so that should accident or mishap occur to the aeroplane, the person is enabled to descend to 20 the ground in safety.

These and other like objects are attained by the novel construction and combination of parts hereinafter described and shown in the accompanying drawings, forming a material part of this disclosure, and in which:—

Figure 1 is a front elevational view, showing a parachute made in accordance with the invention, and indicating its application.

Fig. 2 is a side elevational and sectional 30 view of the parachute extended, the section being taken on line 2—2 of Fig. 3.

Fig. 3 is a top plan view of the same.

Fig. 4 is an enlarged fragmentary view, showing the connecting joints employed.

Fig. 5 is a transverse sectional view taken on line 5—5 of Fig. 4, and

Fig. 6 is a plan view of the parachute when in a folded or inoperative position.

Adapted to be engaged with the waist of 40 a person are semi-circular bands or rings 10, having attached upon opposite sides eyes 11, engaged by suspension rods 12, which extend upward passing over the head of the wearer.

These rods are connected to other eyes 14, firmly secured to the collar 15 of a buoyant sphere 16, adapted to be inflated with highly buoyant gas, as hydrogen, the same being filled through an opening 17, provided with 50 a removable plug 18, the device constituting an adjunct to the parachute as will be understood.

Engaged with the semi-circular rings or bands 10 are a plurality of projections 20

formed with spherical seats 21, adapted to 55 contain balls 22, and engaged with the balls are extending rods 24, secured by stitches 25 with a strong but light textile fabric 26, engaged to the rings 10 at their inner ends and to similar rings 30 at their outer ends, 60 and also to the outer bars 29. These outer, semi-circular bars 30, are provided with lugs 31, which are pivotally engaged at the outer ends of the rods 24.

Secured to one of the adjacent ends of the 65 semi-circular bands 10 is a hook 33, engageable with a pin set in the opposite band, whereby the rear ends of the band may be secured together, while upon the opposite or front ends of the band, the elements 20 are 70 hinged by a pin 35 so that the band can be opened or closed by releasing the hook 33.

Extending outward from the front pair of 75 balls 21 are arms 36 in which are set pins 37, and secured to the pins is a tension spring 38 80 tending to draw the extending arms 36 toward each other. These are normally held, however, in an open position due to a pair of pivoted links 40 attached to lugs 41 at the lower end of the arms 36, the links being 85 connected by a center pin 42, normally in a raised position, so that the wings, which are symmetrical, are held in a normally extended position.

Passing through the front lugs 20 is a 85 plunger having an operating head 46, the plunger being engaged at its end with a bent element 47, making contact with the links 40 at their pivotal point so that the same may be depressed, permitting the 90 spring 38 to retract the wings in an obvious manner.

In operation, the parts being extended as shown in Figs. 2 and 3, the band is opened, pivoting upon the hinge 35 so as to envelop the waist of the wearer, and then closed thereover, the hook 33 holding the wings in operative position, and, due to the action of the links 40, they are extended 95 equally at the sides of the wearer. When 100 it is desired to make use of the parachute, pressure is applied to the knob 46, forcing the links 40 down, breaking the joint and permitting the spring 38, to close the wings into the position shown in Fig. 1, and, as the 105 structure is fully opened at the bottom, air will be entrained therein, acting in the manner of a parachute and appreciably sus-

taining the person to whom the device is attached.

Having thus described my invention what I claim as new and desire to secure by Letters Patent, is—

In a parachute, the combination with a sectional band, a hinged joint therein, and means for holding the opposite edges of said band sections in engagement, of spherical joints formed through the outer edges of said band, rods having spheres engaged with said joints, said rods extending oppositely outward, connecting means engaged with

said rods at their outer ends, a fabric disposed over said band and rods, a pair of arms secured to said rods, a spring attached to the ends of said arms adapted to draw them together, a pair of links pivoted to said arms and to each other centrally of said band, and a plunger passing through said band adapted to depress said links whereby said arms may be collapsed together. 15 20

In testimony whereof I have affixed my signature.

STEPHEN SZÜCS.
